[57] CLAIM

The ornamental design for a screwdriver for interchangeable bits, as shown and described.

DESCRIPTION

FIG. 1 is an elevational view of a screwdriver for interchangeable bits showing our new design;

FIG. 2 is an elevational view of the screwdriver for interchangeable bits rotated 180° from the position seen in FIG. 1; FIG. 3 is a similar elevational view of the screwdriver for interchangeable bits rotated 90° in a counter clockwise direction from the position seen in FIG. 1;

FIG. 4 is a similar elevational view of the screwdriver for interchangeable bits rotated 90° in a clockwise direction from the position seen in FIG. 1;

FIG. 5 is a top end view of the screwdriver for interchangeable bits;

FIG. 6 is a bottom end view of the screwdriver for interchangeable bits;

FIG. 7 is an elevational view of another embodiment of a screwdriver for interchangeable bits showing our new design; FIG. 8 is an elevational view of the screwdriver for interchangeable bits rotated 180° from the position seen in FIG. 7; FIG. 9 is a similar elevational view of the screwdriver for interchangeable bits rotated 90° in a counter clockwise direction from the position seen in FIG. 7;

FIG. 10 is a similar elevational view of the screwdriver for interchangeable bits rotated 90° in a clockwise direction from the position seen in FIG. 7;

FIG. 11 is a top end view of the screwdriver for interchangeable bits; and,

FIG. 12 is a bottom end view of the screwdriver for interchangeable bits.
